EXEMPLARY CLAIM

1. In a guided missile fuze system of the type wherein electromagnetic energy is radiated and a portion of said radiated energy is returned by a reflecting means for actuating a firing circuit the combination for pro-

viding countermeasures against a sweep jammer comprising:

- a. a first fuzing channel responsive to signals received in a first frequency band,
- b. a first firing circuit,
- c. a normally closed relay for connecting said first fuzing channel to said first firing circuit,
- d. a second fuzing channel responsive to signals received in a second frequency band that is higher in frequency than said first frequency band,
- e. a second firing circuit,
- f. a normally open relay for connecting said second fuzing channel to said second firing circuit,
- g. a signal processing channel responsive to signals received in a third frequency band that is higher in frequency than said second frequency band,
- h. relay actuating means responsive to an output from said signal processing channel when signals are received from the sweep jammer for closing said normally open relay for a predetermined period that is less than the time for the sweep to travel from said signal processing channel to said second fuzing channel,
- i. relay actuating means responsive to an output from said second fuzing channel when signals are received from the sweep jammer for opening said normally closed relay whereby said first firing circuit will not fire on the jamming signal.

GUIDED MISSILE FUZE SYSTEM

The present invention relates to guided missile fuze systems and more particularly to guided missile fuze systems which will fuze on jamming signals.

A sweep jammer is described by the following parameters: output power, sweep rate, modulation bandwidth; and total sweep deviation. In order to derive passive information to fuze on the jammer, one or more of these parameters must be determined and acted upon by the fusing system.

An object of the present invention is to provide a fusing system which will (in the presence of jamming signals of sufficient strength to dud or pre-detone the fuze) de-activate the main fuze channel and activate a passive channel that will fuze on a jamming signal source.

Another object of the invention is to provide a fuze system which will function to fuze on a sweep jammer in response to one or more of the parameters defining a sweep jammer.

A further object of the invention is to provide a fusing system which will fuze on a sweep jammer based on information derived from the modulation bandwidth and power of the jammer.

Still another object of the invention is to provide a fusing system which will fuze on a sweep jammer based on information derived from the jammer sweep rate.

Other objects and many of the attendant advantages of this invention will become readily appreciated as the same becomes better understood by reference to the following detailed description when considered in connection with the accompanying drawings wherein:

FIG. 1 is a block diagram of a fusing system which relies on jammer modulation bandwidth and power information to fuze on the jammer.

FIGS. 2 and 3 are block diagrams of fusing systems which rely on the jammer sweep rate information to fuze on the jammer.

Referring now to the drawings, wherein like reference characters designate like or corresponding parts throughout the several Figures, there is shown in FIG. 1 a fusing system having three channels for processing signals received at antenna 22. In describing the present invention only that portion of the fusing system is described which is necessary for receiving and processing reflected signals from a target or signals received from a jammer. Channel 12 comprises a normal detector circuit and may be of any of the detector circuits shown and described in copending application Ser. No. 789,459, filed Jan. 27, 1959 by Carlton H. Cash. Channel 14 is an automatic gain control circuit and is of the same bandwidth as channel 12 but tuned adjacent to channel 12 on the high frequency side. The output from channel 14 is fed to channel 12 as a negative feedback so that the gain of channel 12 is reduced as the strength of jamming signals increase. Relay 18 is also connected to the output of channel 14 and will operate to de-activate channel 12 when jamming signal strength is sufficient to saturate channel 12. Channel 16 is a passive channel and is tuned to a higher frequency than channel 14.

In operation channels 12 and 14 are operating in the normal manner. The signal is received at antenna 22, mixed with a local oscillator signal in mixer 10 to obtain doppler signal which is fed to channel 12 and 14. If a signal is received with the proper characteristics, an output will appear in channel 12 which is fed through

relay 18 to firing circuit 20. In the presence of sweep jamming, signals from the jammer will saturate channel 12 and cause dudding. When jamming energy is received in channel 14, relay 18 is energized. Functionally, this disconnects channel 12 from firing circuit 20 and connects channel 16 to firing circuit 20. The jamming signal received in channel 16 is processed and provides an output signal which activates firing circuit 20. Thus, jamming energy must appear in channels 14 and 16 simultaneously. By tuning channel 16 to a frequency greater than that of channel 14 having a bandwidth equal to the expected interference bandwidth plus one-half the bandwidth of channel 16, the requirement that the jamming signal simultaneously be in channel 16 is avoided. Thus, providing control over the minimum noise modulation bandwidth sweep jammer that will be allowed to trigger the system. The following parameters have been found satisfactory in practicing the invention: Channel 12 centered at the 3rd harmonic of the modulation frequency ($3f_m = 2.505$ mc) with a bandwidth of 200 kc. Channel 14 is tuned adjacent to the high frequency side of channel 12 with a bandwidth of 200 kc. Channel 16 is tuned to 10.8 mc with a bandwidth equal to the expected jammer bandwidth.

Referring to FIG. 2 an additional relay 24 is provided to interrupt the connection of channel 14 to relay 18. Channels 12, 14 and 16 operate at the same frequencies as in FIG. 2. Channel 16 performs a different function than in the system of FIG. 1. Referring to FIG. 2, the operation of the system is as follows. The jamming signal enters channel 16, which energizes relay 24 and removes channel 14 from the system and leaves channel 12 operating without AGC. Relay 24 is allowed to remain energized for a time which is less than the time between the leading edge of the jamming signal leaving channel 16 and entering channel 14. It has been found that with channel 16 operating at a center frequency of 35 mc, firing on a sweep jammer is prevented. For example, with a 50-mc wide sweep jammer, the sweep enters channel 16 and enables channel 14 for 1.5 milliseconds. By the time the sweep reaches channel 14, relay 24 has closed and channel 14 is operating again so that a dudding effect occurs. Referring to FIG. 3, channels 12 and 14 are operating at the same frequency as in FIG. 2. Channel 16 is passive and operates at the same frequency as in FIG. 2. The system of FIG. 3 differs from the system of FIG. 2 in the position of relay 22 in the output circuit of channel 14. In operation, when sweep jammer enters channel 16, relay 24 is energized and remains open for a period of time which is less than the time for the sweep to travel from channel 16 to channel 14. During this time interval there will be energy in channel 14 and firing circuit 26 will not be activated. When the jammer does enter channel 14, firing is prevented by the AGC action. Firing circuit 26 is provided so that the firing threshold for a jammer signal is higher than a target return signal. With the gain of channels 12 and 14 approximately equal and the sensitivities of firing circuits 20 and 26 equal, the system is susceptible to firing on a sea-return signal, for example, when sweep jammer entered channel 16. If the threshold of firing circuit 26 is set 30 db above firing circuit 20, then it requires a signal in channel 14 at the same power level as the jammer, in order to activate firing circuit 26. This would require the sea-return signal to be 30 db above target threshold to cause detonation in the presence of a sweep jammer,

and for such a high sea-return power the system would be dudded.

Obviously many modifications and variations of the present invention are possible in the light of the above teachings. It is therefore to be understood that within the scope of the appended claims the invention may be practiced otherwise than as specifically described.

- d. a second fuzing channel responsive to signals received in a second frequency band that is higher in frequency than said first frequency band,
- e. a second firing circuit,
- f. a normally open relay for connecting said second fuzing channel to said second firing circuit,
- g. a signal processing channel responsive to signals received in a third frequency band that is higher in frequency than said second frequency band,
- h. relay actuating means responsive to an output from said signal processing channel when signals are received from the sweep jammer for closing said normally open relay for a predetermined period that is less than the time for the sweep to travel from said signal processing channel to said second fuzing channel,
- i. relay actuating means responsive to an output from said second fuzing channel when signals are received from the sweep jammer for opening said normally closed relay whereby said first firing circuit will not fire on the jamming signal.
